UNITED STATES PATENT OFFICE.

CALVIN H. LEHMAN, OF JOHNSTOWN, PENNSYLVANIA.

DESIGN FOR A SMOKER'S SET.

Application filed April 16, 1925. Serial No. 13,149. Term of patent 14 years.

To all whom it may concern:

Be it known that I, CALVIN H. LEHMAN, a citizen of the United States, residing at Johnstown, in the county of Cambria and State of Pennsylvania, have invented a new, original, and ornamental Design for a Smoker's Set, of which the following is a specification, reference being had to the accompanying drawing, forming part thereof.

The figure is a perspective view of the smoker's set, showing my new design.

I claim:

The ornamental design for a smoker's set as shown.

CALVIN H. LEHMAN.
